UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Original application filed February 26, 1921, Serial No. 448,047. Divided and this application filed October 16, 1924. Serial No. 743,894.

To all whom it may concern:

Be it known that I, JOHN WALDHEIM, a citizen of the United States, residing in Elizabeth, in the county of Union and State of New Jersey, have invented certain new and useful Improvements in Typewriting Machines, of which the following is a specification.

The present invention relates to typewriting machines of the continuous billing variety, one form of which is set forth in the patent to Wernery and Smith, No. 1,132,055, granted March 16, 1915, and provides a means for trimming the side edges of a fan-fold web used in such machines, thus remedying such objections which have arisen in connection with the use of such webs in machines of this type:

The fan-fold webs used in continuous billing machines are perforated at their edges to facilitate the folding and the accurate superposing of the printed forms. When the sheets of the web are separated after typing, the perforations leave a ragged edge which detracts from the general appearance of the bill. Users of fan-fold webs sometimes trim the side edges of the webs before introducing them into the machine. This is objectionable, however, since the separate sheets tend to creep relatively to each other in the operation of feeding them around the platen while typing the forms. It is therefore desirable to trim the side edges of the web in such manner as to provide smooth edges on the separate sheets without permitting creeping of the sheets. For this purpose there is mounted at the rear of the carbon-paper carriage, at each side thereof, a circular cutting blade exterior to the web and disposed in a plane at right angles to that of the web and inclined to the side edge thereof, so as to project into said web, and a guide co-operates with each cutting blade for guiding the web into the cutting blades, so that, upon retraction of the carbon-carrier, the knives will trim off and throw aside portions of the edges of the web and separate the latter into sheets. This is done at the portion of the web which is not separated or spread by the carbon-holding blades, between which the web is threaded. Only the portion about to be typed is trimmed, the remainder of the web remaining united at the edges, thus guarding against relative

shifting of the sheets. The rapid rearward movement of the sharp blades and co-operating guides will result in a clean cut, leaving the separate sheets of the web with smooth, even edges. Means may be provided for adjusting the height of the cutting blade, and also the distance which the blade projects into the web.

To obviate the necessity of frequently changing the blades, they may be circular in form so that progressive sharp portions of the periphery may be utilized in place of the used, dull ones.

This application is a division of my co-pending application, Serial No. 448,047, filed February 26, 1921, now Patent No. 1,533,707, dated April 7, 1925.

Other features and advantages will hereinafter appear.

In the accompanying drawings,

Figure 1 is a top plan view of the carbon-carrier and shaving knives at both edges of the fan-fold web, with parts broken off.

Figure 2 is a longitudinal vertical section through Figure 1.

Figure 3 is a perspective view of one of the circular cutting knives in operative cutting relation with the web and its guide.

Figure 4 is a small diagrammatic side view illustrating the co-operative relations between carbon-carrier and cutter to the work-sheets and platen.

In the drawings, 10 is a platen of the fan-fold machine of the type disclosed in the aforesaid Wernery and Smith patent. The platen forms part of the usual carriage (not shown) which is provided with a rearward extension comprising side rails 11 which form runways for a carbon-carrier or carriage 13. A web of work-sheets 20 is fed from any suitable source from the rear to and over carbon-carrier 13, over guide-bar 21, and thence under and around the platen to the printing point.

The carbon-carrier is provided with the usual stepped side-supporting members 22, having detachably connected therewith the inwardly-extending carbon attaching bars or fingers 23, said fingers being projected alternately from opposite sides at different levels so as to enter between the alternate folds of the fan-fold web. Carbon sheets 24, attached at their ends in any suitable manner to said bars 23, are interleaved be-

tween the folds of the web. The carbon-carrier and its attached carbon sheets are free to move forwardly with said web during the line-spacing operation when the set 5 of forms is being typed. When said set of forms has been typed the platen is raised as described in said patent to Wernery and Smith and the forms may be straightened out. The carbon-carrier is then retracted by 10 pushing upon handle 25 extending forwardly from the carrier 13. The platen may then be lowered to printing position and the set of typed forms severed.

The present invention comprises means 15 mounted on the carrier 13 for trimming the side edges of that portion of the web about to be typed. For this purpose, the carbon-carrier is provided at each side with a rearward extension 29, at the extreme forward 20 end of which is mounted a U-shaped guide 30 having a narrow horizontal opening 31 through which the web is designed to pass. The web is closely held or its plies are compacted by the guide, and emerges from the 25 guide at the forward end thereof as a compact mass of sheets, which renders it easier to trim than if the layers of web were widely separated. Adjacent the forward end of the 30 guide 30 is therefore mounted a rearwardly-facing circular knife 32 whose plane may be substantially perpendicular to the plane of the web, and inclined with respect to the edge of said web. The rearward edge of the knife comprising an inclined cutting 35 edge, to effect a draw-cut along the edge of the web, projects inwardly beyond the edge of the web to a distance equal to the amount which it is desired to trim the edge of the web. The knife 32 is mounted upon a clamp 40 screw 33 passing through the knife 32 and lodging in block 35. To enable the knife to be adjusted to such height that it meets the web properly as it emerges from the guide, the block 35 is adjustably mounted for vertical movement by means of a shouldered 45 screw 36 passing into said block, through a slot 37 in a vertical standard 38 having a base portion 39, whereby it is fastened on the carbon-carrier. It should be noted that, 50 due to the inclined cutting edge of the knife 32, the width of the margin cut off at each side of the fan-fold web depends upon the vertical adjustment of the knife as well as upon the horizontal adjustment thereof. 55 The guides 30 may be adjustable sidewise to the edges of the web to guide said web laterally. The side guides (not shown) which are usually mounted on the bar 21 may be used to assist in guiding the web to 60 the platen.

In operation, the knife 32, having been adjusted vertically to meet the web as it emerges from the guide, and to trim the proper amount of the edge of the web, will 65 shave off the side edge of the web for a dis-

tance substantially equal to the length of one form every time the carriage is retracted, since the web remains stationary while the carriage travels rearwardly. Preferably each knife 32 is beveled only on its inner 70 face to form the cutting edge, thus leaving at the outer face a plane surface by which the severed edge portions of the web will be directed outwardly over the sides of the track for the carbon-carrier 13 at the rear 75 of the carbon-carrier proper.

When a used portion of the cutting periphery becomes dull, the operator loosens the screw 33 and turns the knife to obtain a sharp portion, after which the knife may 80 be fastened in place by said screw. The life of the knife is therefore multiplied and obviates frequent changing of knives, a particularly desirable feature in a machine subjected to heavy use. 85

It will be seen that the cutter in Figure 3 is adjustable up and down relatively to the web by means of the screw 36 passing through the slot 37 and threaded into the block 35, so that the active cutting edge may 90 be inclined from the front to the rear of the web.

Further it will be understood that the superposed layers of the fan-fold web extend from side to side, and that they are usually 95 folded at both sides of said web, as indicated in Figure 1, in which case two cutters are provided, one at each side of the web. Sometimes, however, the layers are folded only along one edge of the web, in 100 which case only one cutter is necessary.

In a machine of this character so long as the fan-fold web is of a single or standard width, the adjustment of the circular cutter to the edges of the web may be permanent 105 when once correctly set, and hence the circular form of cutting element may be interchangeable at all times without readjustment to the trimming line along the edges of the web; and an exchange of a dull for 110 a new cutter can be readily made.

Variations may be resorted to within the scope of the invention, and portions of the improvements may be used without others.

Having thus described my invention, I 115 claim:

1. In a typewriting machine having a carriage, and a platen over which a fan-fold web may be fed, the combination with a reciprocating carbon-carrier controlling 120 carbon inlays between the plies of the web, of a circular cutter traveling with the carrier and effective to trim off the side edges of the web, said cutter being adjustable about a fixed axis, whereby new cutting edges may be presented to the web, and means to clamp said cutter stationary on the carrier, in adjusted position.

2. In a typewriting machine having a 125 carriage and a platen over which a fan- 130

- fold web with carbon inlays may be fed, the combination with a carrier to retract the carbon inlays after each printing operation, of a web side-fold cutter adjustably fixed to the carrier and having a continuous cutting edge that may be positioned, at will, to substitute a keen web-cutting edge for a dull used edge.
3. In a typewriting machine having a carriage and a platen over which a fan-fold web of paper with carbon inlays may be fed, the combination with a reciprocating carrier to retract the carbon inlays after each printing operation, of an adjustably fixed cutter having an endless cutting edge, mounted on the carrier and effective to trim off the side-edges of the web during the movement of the carrier to retract the carbon inlays, said cutter enabling presentation of any selected portion of said endless cutting edge to the web.
4. In a typewriting machine having a revoluble platen over which a continuous fan-fold web of work-sheets with carbon inlays may be fed around the platen, the combination with a reciprocating carbon-carrier, of edge-trimming means moving with the carrier, including a cutter having a continuous or endless cutting edge, and a support upon which said cutter is held stationary, said cutter being adjustable on the support whereby to present any portion of said cutting edge to the web without readjustment to the predetermined trimming line on said web.
5. In a typewriting machine having a carriage and a revoluble platen over which a continuous fan-fold web of work-sheets with carbon inlays may be fed, the combination with a reciprocating carrier for the carbon inlays to withdraw the carbon after the printing operation, of a bracket secured to the carrier exterior to the web, a block adjustably secured to the bracket, and a knife having a continuous cutting edge adjustably clamped to the block, whereby any selected portion of said cutting edge may be presented to the web and then clamped in such position.
6. In a typewriting machine having a carriage and a revoluble platen over which a continuous fan-fold web of work-sheets with carbon inlays may be fed, the combination with a carrier to withdraw the carbon inlays after the printing operation, of a bracket secured to the carrier, a block slidably mounted on the bracket for vertical adjustments, and side-edge-trimming means adjustably fixed to the block, including a cutter having an endless cutting edge that may be shifted, at will, to substitute a keen-edge section for a dull one, the vertical adjustment of said block effecting a variation in the angle of said cutting edge operating upon the web.
7. In a typewriting machine having a carriage and a revoluble platen over which a fan-fold web of work-sheets with carbon inlays may be fed, the combination with a reciprocating carrier for the carbon inlays, of a bracket secured to the carrier, a movable block adjustably secured to the bracket, and side-edge-trimming means adjustably fixed to the block to assume an angular position relative to the web, including a knife with an endless cutting edge, any portion of which may be brought into cutting relation with the web without changing the sidewise adjustment of said cutter.
8. In a typewriting machine having a platen over which a fan-fold web may be fed, the combination with a reciprocable carbon-carrier for withdrawing carbon-sheets from a used portion of the fan-fold web, of adjustable smooth-trimming means mounted on said carbon-carrier at its rear and rendered effective, upon a withdrawing operation of said carbon-carrier, to cut off a portion of the folded side edges of a section of said fan-fold web and leave smooth edges upon the disconnected plies, said trimming means including for each side at which trimming is to be effected a knife to cut all of the plies, the knife having an endless cutting edge and being in a plane perpendicular to the web, the knife also being inclined with respect to the side edges of the web, any portion of said edge being positionable in adjusted cutting relation with the web, and means to permit the width of the trimmed-off portion to be varied, including an adjustable vertical mounting for the knife, whereby the knife moves inwardly or outwardly with reference to the adjacent side of the web when said knife is being adjusted vertically.

JOHN WALDHEIM.
